ABSTRACT OF THE DISCLOSURE

A bobbin-wound electrical coil has its ends soldered to conductor ends of insulated coil leads within the peripheral confines of the bobbin, with the leads extending with a loose fit through holes in one of the opposite flanges of the bobbin, and having next to their coil-connected ends enlarged collar formations on their insulation which lock the leads against retraction from the bobbin.

This invention relates to electrical coils in general, and to bobbin-wound coils with thereon anchored coil leads and a method of anchoring them thereon in particular.

Coil leads, which are usually solder-connected with the ends of bobbin-wound coils, are anchored to the bobbins in various ways of which the more common ones involve string ties, fabric and adhesive tapes, or staples and cards, for securing the connected leads against separation from the coils in installing or otherwise handling the latter. While these lead anchors on coils are generally satisfactory, they are objectionable in a few, but important, respects. Thus, the formation of these lead anchors is a tedious and time-consuming task involving considerable cost in any event. Furthermore, these lead anchors usually add considerable bulk to the coils and frequently cause local bulging of the coils beyond the bobbin peripheries with ensuing likely interference in mounting the coils in crowded spaces. Moreover, lead anchors involving staples and cards are liable to cause coil failure by cutting through the insulation on leads either on application of the staples or on their subjection to pressure in mounting the coils. Even more important, these lead anchors just barely meet the minimum pull-test requirements of withstanding a pull of a specified number of pounds for a specified time period.

It is among the objects of the present invention to provide a bobbin-wound coil with thereto connected insulated coil leads of which the latter are anchored to the bobbin in a manner in which the lead anchors are devoid of any of the objections, and are also in other respects superior, to the aforementioned lead anchors on bobbin-wound coils.

It is another object of the present invention to provide a bobbin-wound coil of which the thereto connected coil leads are anchored to the bobbin by positive interlock with the latter of the insulation on the coil leads near their coil-connected conductor ends, so that any pull on the coil leads outside the bobbin is wholly taken up by the bobbin and no part thereof is transmitted to the coil-connected lead ends. With this arrangement, the anchorage of the coil leads to the bobbin is incomparably firmer than the aforementioned different lead anchors, with the present lead anchorage safely resisting a pull on the leads of any magnitude short of that at which the interlock will break.

It is a further object of the present invention to provide a bobbin-wound coil with thereto connected coil leads in which, for the aforementioned interlock between the bobbin and insulation of the coil leads, there are provided in preferably one of the opposite endflanges of the bobbin between its outer periphery and the wound coil therein two

2

apertures through which the coil leads extend with a loose fit to the outside of the bobbin, and the insulation of each coil lead has within the peripheral confines of the bobbin an enlarged collar-like formation which on outward pull on the lead is firmly drawn against the inner face of the associated endflange of the bobbin so that the entire pull force is taken up by this endflange. While with this arrangement the anchorage of each coil lead to the bobbin is particularly firm, there is this further advantage that each coil lead may advantageously be assembled with the bobbin and anchored thereto before being connected with the respective coil end, whereby the task of making the connection is considerably facilitated and not even an accidental pull on the lead will interfere with this task or

adversely affect the connection. Moreover, each anchored lead has some freedom of sliding movement into the bobbin for any give to permit its quickest, easiest and most secure, connection with the respective coil lead outside of the narrow bobbin confines. Further, with each lead anchor being entirely within the confines of the bobbin, it is entirely natural as well as advantageous to also confine the connection of each lead with its coil end within the bobbin and still afford therewithin ample space for a usual protective outer wrapping on the coil.

Another object of the present invention is to provide a bobbin-wound coil with thereto connected coil leads of which the aforementioned collar-like formations on the insulation of the coil leads are preferably and advantageously integral parts of the insulation.

A further object of the present invention is to devise a method of forming the aforementioned integral collar-like formation on preferably thermoplastic insulation of each coil lead, according to which an endlength of the insulation next to an exposed conductor end of the lead is heated to a semiplastic state, and while in such semiplastic state is by a tool upset around the conductor therein, with ensuing backward displacement of such insulation on the conductor and its simultaneous outward spread into the collar-like formation.

It is another object of the present invention to provide in the aforementioned method for heating an endlength of the insulation next to an exposed conductor end of the lead, by advantageously applying heat to its exposed conductor end for transfer of this applied heat by the latter to the nearby insulation, and then upsetting the thus heated insulation with a cold tool. With this mode of heating the insulation to semiplasticity, the insulation may be kept fully exposed and, hence, cannot stick to anything, and with the upsetting tool being cold, this insulation will readily be upset thereby with negligible force and will quickly set without having a chance to stick to the tool.

It is still another object of the present invention to further provide in the aforementioned method for assembling the coil leads with the bobbin by passing them with their other ends from the inside of the bobbin through the apertures in one of the endflanges thereof to the outside, and then connecting their exposed conductor ends next to their upset insulation ends to the respective coil ends, preferably by bringing these conductor and coil ends outside the narrow confines of the bobbin and there quickly intertwisting the respective ends and then simply dipping them in a solder bath without any impediment from the bobbin. With this enhanced method, the task of electrically connecting the coil ends and ends of the respective coil leads is of the aforementioned considerable facility, and these connected coil and lead ends may subsequently be readily stowed, or simply turned, into the confines of the bobbin for optimum protection therein.

Further objects and advantages will appear to those skilled in the art from the following, considered in conjunction with the accompanying drawings.

In the accompanying drawings, in which certain modes of carrying out the present invention are shown for illustrative purposes:

FIG. 1 is an end view of a bobbin-wound coil with connected and anchored coil leads according to the invention;

FIGS. 2 and 3 are side and top views of the same coil;

FIG. 4 is a view of one of the coil leads of the bobbin-wound coil;

FIGS. 5, 6 and 7 show progressive steps in forming the coil lead of FIG. 4 with an anchor formation;

FIGS. 8 and 8A show progressive steps in electrically connecting the coil leads with the ends of the bobbin-wound coil; and

FIG. 9 is an end view of a bobbin-wound coil with connected and anchored coil leads according to a modification of the invention.

Referring to the drawings, and more particularly to FIGS. 1 to 3 thereof, the reference numeral 10 designates a bobbin-wound coil of which the bobbin 12 is of any suitable insulating material, such as plastic, for example, and has opposite end flanges 14 that flank the wound coil 16. The coil 16 of bare conductive wire is wound directly in the bobbin 12 in conventional manner, with the opposite wire ends 18 of the coil 16 extending beyond the outer coil periphery. As usual, the coil 16 is held against unraveling by a few turns of adhesive tape *t* or the like on its outer periphery, with the coil ends 18 being passed above the tape for connection with coil leads 20.

Each of the coil leads 20 has an electrical conductor 22 with an insulation coating 24, with opposite ends 26 and 28 of the conductor being stripped of insulation for electrical connections. In this instance, the bare conductor ends 26 of the coil leads 20 are electrically connected with the respective coil ends 18 as at 30.

Each coil lead 20 is also anchored to the bobbin 12 to prevent its disconnection from the respective coil end 18 on subjection of the lead to pull or other forces. To this end, and in accordance with an important aspect of the present invention, each coil lead 20 is with its insulation 24 interlocked with the bobbin 12 against removal therefrom that would break its connection with the coil 16. In this connection, the opposite flanges 14 of the bobbin are, as usual, of larger outside diameter than the coil 16, so that these flanges have peripheral margins 32 which extend beyond the outer coil periphery. There are provided in the flange margins 32, and in this instance only in one flange margin 32', two spaced identical apertures 34 through which the coil leads 20 extend with a relatively loose fit of their insulation 24 therein, with the greater lengths of the coil leads projecting outside the bobbin 12 for connection with their ends 28 in an intended circuit. The coil leads 20 have, at the ends of the insulation coatings 24 next to their coil-connected ends 26 and within the peripheral bobbin confines, outward collar formations 36 which by abutment against the inner face 38 of the flange margin 14' lock these coil leads against outward removal from the bobbin. Thus, with these collar formations 36 on, and coil-connected ends 26 of, the coil leads 20 being within the peripheral confines of the bobbin and also preferably held therein by a few turns of adhesive tape or the like thereover (not shown), the only way the coil lead connections with the coil could be torn apart would be pull forces on the coil leads outside the bobbin, but such pull forces of most any magnitudes are wholly taken up by the described anchors of the coil leads on the bobbin and are in no ways transmitted to the coil lead connections with the coil.

The insulation 24 of each coil lead 20 is of plastic, and preferably thermoplastic, which is extruded in usual manner onto the conductor 22. The collars 36 on the insulation coatings 24 of the coil leads 20 are formed as integral parts of these coatings in accordance with a method which is part of the present invention. To begin with, the collars 36 are formed on the insulation coat-

ings 24 of the coil leads 20 preferably before the latter are assembled with the bobbin 12. According to the method just mentioned, the end of the insulation coating 24 next to the bare conductor end 26 of each coil lead is in any suitable manner heated to semiplasticity, whereupon this end part of the coating, while still in a semiplastic state, is upset, with ensuing strip-back of insulation on the conductor and simultaneous spread of the same into the collar formation 36. Preferably and advantageously, this end part of the coating of each coil lead 20 is heated by heating the nearby bare conductor end 26 which transmits the applied heat to the coating. This may be achieved by contacting the bare conductor end 26 with an electrically or otherwise heated element 42 (FIG. 5), from which it will be retracted after a given short time interval when the end part 40 of the coating is known to be in proper semiplastic state for its immediately following formation into the collar 36 by upsetting.

For upsetting the semiplastic end part 40 of the coating 24 of each coil lead 20, recourse may be had to a tool 44 having a bore 46 and a counterbore or recess 48 (FIGS. 6 and 7), of which the bore 46 is of a diameter to receive the conductor end 26 of the coil lead with a relatively loose fit, while the recess 48 is of a diameter which may be the same as, but preferably is slightly larger than, the diameter of the collar 36 to-be-formed. Thus, while the end part 40 of the insulation coating 24 on the coil lead 20 is still in a semiplastic state, the coil lead is with its conductor end 26 passed into the tool 44 and into the bore 46 therein (FIG. 6), and is then quickly thrust all the way into the tool (FIG. 7), whereby the ring-like shoulder 50 formed by the bottom of the recess 48 upsets the end part 40 of the coating which, in consequence, is formed into the collar 36. While the described preferred heating to semiplasticity of the end part 40 of the coating 24 via the conductor end 26 (FIG. 5) is advantageous for several reasons, including no contact of the semiplastic insulation with anything to which it might stick, non-sticking of this semiplastic insulation also prevails in the upsetting operation in that the contact area between this insulation and the upsetting shoulder 50 is quite small, and the tool 44 is used in a cold state in which it helps to expedite setting of the insulation over its small contact area therewith. Moreover, the described thrust of the semiplastic end part of the insulation against the upsetting shoulder 50 is preferably quite brief and, hence, non-conducive of sticking of the insulation to this upsetting shoulder.

While the formation of the collar 36 on the insulation coating 24 of each coil lead 20 according to the method just described is particularly effective where the insulation is of thermoplastic material, the same method is also effective to produce an adequate collar-like formation on insulation which is of vulcanized rubber or rubber-like material. Thus, on heating the latter kind of insulation and upsetting the same while still heated, the insulation will undergo sufficient permanent deformation into a collar-like formation adequate for the purpose of secure coil lead anchorage to the bobbin.

Preferably and advantageously, the bobbin-wound coil 10 and coil leads 20 are assembled according to a method which is also part of the present invention. Thus, after first forming the collars 36 on the insulation coatings of the separate coil leads 20 as described, these coil leads are next anchored to the bobbin 12 by simply passing them, with their conductor ends 28 leading, through the respective apertures 34 in the flange margin 14' of the bobbin from inside the latter to the outside thereof. Next, the coil ends 18, which as already mentioned are left sufficiently long for their outward extension beyond the peripheral bobbin confines, are drawn out from the bobbin confines if they are not already so extended, and the conductor ends 26 of the anchored coil leads are similarly extended outwardly from the peripheral bobbin confines where each conductor end 26 is initially connected with

a coil end 18 by simply intertwisting them at 52 without any impediment from the bobbin (see also FIG. 8), whereupon the thus initially connected pairs of conductor and coil ends 26 and 18 are dipped in a solder bath *b* (FIG. 8A) to finish their connection. These pairs of finish-connected conductor and coil ends 26 and 18 are then stowed back into the peripheral confines of the bobbin preferably into close proximity to the tape-covered coil 16 (FIG. 2) for application of a final outer tape wrapper thereover (not shown). Stow-back of the connected conductor and coil ends into the peripheral bobbin confines is achieved in simple manner by turning the coil leads 20 on the outside of the bobbin. Further, the collars 36 on the insulation of the coil leads 20, by which the latter are anchored to the bobbin 12, afford some freedom of inward motion of the coil leads in the bobbin and, hence, temporary outward extension of the conductor ends 26 from the bobbin to any extent matching that of the coil ends 18 for their intertwisting (FIG. 8) with the least impediment from the bobbin 12. Of course, if for the connection of the conductor ends 26 with the coil ends 18 the anchored coil leads 20 are moved with their collars 36 slightly inwardly and away from the flange margin 14' of the bobbin as in FIG. 8, for example, the coil leads are subsequently preferably pulled back with their collars 36 into abutment with the flange margin 14' before applying the beforementioned final outer tape wrapper.

Reference is now had to FIG. 9 which shows a modified bobbin-wound coil 10a with attached and anchored coil leads 20a. In this modified coil construction the flange margin 32a' of the bobbin 12a is devoid of apertures through which the coil leads extend, and is instead provided with two radial slots 60 in its outer periphery into which the coil leads 20a are conveniently inserted laterally. Adhesive tape or the like *p* may then be applied to the bobbin to close the open ends of the slots 60 and lock the coil leads 20a against lateral removal therefrom.

What is claimed is:

1. Anchorage of a pair of coil leads on a bobbin with a wound-in coil having outer exposed ends, with the coil leads being insulation-coated electrical conductors having insulation-bare ends connected with said coil leads, respectively, which comprises opposite coil-flanking flanges on the bobbin each with a peripheral margin extending

outwardly beyond said coil, and two apertures in said flange margins through which said leads extend with sliding freedom; and a collar on each coil lead formed by a cross-sectionally enlarged part of the insulation thereof and located between said flange margins, with the collar on each coil lead being of larger cross-sectional dimension than the aperture in the associated flange margin through which the lead extends, whereby each collar will have some play to and from the associated flange margin and will be held in forced abutment therewith by the respective lead when the latter is strained for retraction from the bobbin outwardly through the aperture through which it extends.

2. Coil lead anchorage as in claim 1, in which said collar-like formations are provided on the ends of the insulation of said coil leads next to their respective coil-connected ends.

3. Coil lead anchorage as in claim 1, in which each of said apertures is formed by a radial slot in the outer periphery of its flange.

4. Coil lead anchorage as in claim 3, in which each of said slots is at the outer periphery of its flange closed by a crossing tape secured to said flange.
